UNITED STATES PATENT OFFICE.

FRANK ZIDAR, OF DETROIT, MICHIGAN.

DESIGN FOR A RADIO OUTFIT CABINET.

Application filed February 3, 1923. Serial No. 5,064. Term of patent 14 years.

To all whom it may concern:

Be it known that I, FRANK ZIDAR, a native of Yugoslavia, residing at 3171 Third Avenue, in the city of Detroit, county of Wayne, State of Michigan, have invented a new, original, and ornamental Design for a Radio Outfit Cabinet, of which the following is a specification, reference being had to the annexed drawing, forming part thereof.

Figure 1 is a front elevation of my radio outfit cabinet, showing my new design;

Fig. 2 is a side elevation of the same, and

Fig. 3 is a rear elevation of the radio outfit cabinet.

I claim:

The ornamental design for a radio outfit cabinet as shown.

FRANK ZIDAR.
